UNITED STATES PATENT OFFICE.

FLOYE A. DAVIS, OF SONESTOWN, PENNSYLVANIA.

RAILROAD-TIE.

1,169,014.

Specification of Letters Patent. Patented Jan. 18, 1916.

Application filed August 14, 1915. Serial No. 45,540.

To all whom it may concern:

Be it known that I, FLOYE A. DAVIS, a citizen of the United States, residing at Sonestown, in the county of Sullivan and State of Pennsylvania, have invented certain new and useful Improvements in Railroad-Ties; and I do hereby declare the following to be a full, clear, and exact description of the invention, such as will enable others skilled in the art to which it appertains to make and use the same.

This invention relates to new and useful improvements in railroad ties and the principal object of the invention is to provide a tie which will prevent rails from sinking, creeping or spreading.

Another object of the invention is to provide a device which will avoid the necessity of using a gage to insure the proper spacing of the rails.

A further object of the invention is to provide a novel means for attaching the rails to the tie which enable the same to be easily and quickly removed in order that new rails may be substituted therefor.

With these and other objects in view, the invention consists in the novel combination and arrangement of parts which will be fully set forth in the following specification and accompanying drawings, in which:

Figure 1 is a top plan view showing my improved tie as it would appear when in use. Fig. 2 is a side view in elevation. Fig. 3 is a transverse sectional view on line 3—3 of Fig. 1, and Fig. 4 is a vertical view on line 4—4 of Fig. 2.

Referring now to the drawings by characters of reference, the numeral 1 designates the body of the tie formed of metal, concrete or a similar substantially indestructible material. This tie is formed at each end with a shoulder 2 forming an abutment 3 as clearly shown in Fig. 2. The upper face 4 of each shoulder lies in a plane with the upper face 5 of the central portion of the tie and the inclined faces 6 extend from the central portion 5 to each shoulder as clearly shown in Fig. 2.

Formed in the tie at the point where the faces 6 join the face 5 are the recesses 7 in which the cushioning blocks 8 seat. Formed at spaced distances with relation to the recesses 7 and extending transversely of the tie in parallel relation to the recesses are the keyhole slots 9 in which the bolts 10 are slidable. The shanks of the bolts extend up-

wardly through the slots and beyond the upper faces 5 and 6 and provide a means by which the rail securing members are held in place.

The central rail securing member is designated generally by the numeral 11 and comprises the body 12 formed at each end with a notch 13 which forms the tongue 14 providing the rail flange engaging portion. 65 This plate or body 12 is formed with a plurality of openings through which the bolts 10 extend and it will be seen that when the bolts are placed in position and the nuts slipped over the ends thereof the plate 11 70 will be held in place thus spacing the rails to the proper gage.

Coöperating with the rail securing plate 11 are the plates designated generally by the numeral 15 comprising the body 16, one 75 end of which is provided with the rail flange engaging portion 17, while the opposite end is inclined as at 18 to firmly lie against the face 3 of the shoulder 2. It will be noted that the plate 16 is of a thickness equal to 80 the height of the shoulder and that the same is held in place in the manner identical with the securing means of the plate 11.

It will be apparent from the foregoing that in use the ties are laid in the usual manner and the rails are then positioned on the upper face so that they rest on the cushioning blocks 8 and the inner flanges thereof lie beneath the tongues 14 and it will thus be seen that the rails are spaced to the proper gage. The rail securing members 16 are then secured in place on the inclined faces 6 and it will thus be seen that the tongues 17 overlie the outer flanges of the rails and hold the same firmly in place. It 95 will be obvious that the seats 18 of the rail securing plates 15 abut the inner faces 3 of the lugs 2, thereby preventing outward movement of the rails and the plates.

While in the foregoing there has been shown and described the preferred embodiment of this invention, it is to be understood that such changes may be made in the combination and arrangement of parts as will fall within the spirit and scope of the appended claims.

What is claimed is: —

1. A railroad tie comprising a body, shoulders formed at the ends of the body, the upper face of the central portion of the body extending in a plane with the upper face of each shoulder for a distance equal to

a gage of the track, downwardly inclined faces formed on the body at the ends of the central portion, the body being formed at the points where the inclined faces join the central portion with recesses and also having keyhole slots extending transversely of its upper face, cushioning blocks positioned in the recesses, rail securers on the upper face of the tie and bolts slideable in the keyhole slots and extending through the securers to hold the same in place on a tie.

2. A railroad tie comprising a body, shoulders formed at each end of the body, the upper face of the tie lying in a plane with the upper face of the shoulders between the rails, the portions of the tie intermediate

the upper face and the shoulders being downwardly inclined, the point where the inclined faces join the upper face of the tie being provided with recesses, cushioning blocks within the recesses, the tie being formed at spaced intervals with transversely extending keyhole slots, bolts in the slots and means secured to the tie by means of the bolts to hold railroad rails in place on the cushioning blocks.

In testimony whereof I affix my signature in presence of two witnesses.

FLOYE A. DAVIS.
